UNITED STATES PATENT OFFICE

154,985

DESIGN FOR A PHOTOGRAPHIC CAMERA

Lucien Antoine Regis Bouchetal, Lyon, France

Application October 8, 1947, Serial No. 141,811
In France June 27, 1947

Term of patent 14 years

(Cl. D61—1)

To all whom it may concern:

Be it known that I, Lucien Antoine Regis Bouchetal, a citizen of the French Republic, residing in Lyon (Rhone), France, have invented a new, original, and ornamental Design for Photographic Cameras, of which the following is a specification, reference being had to the accompanying drawing, forming part thereof.

Fig. 1 is a front perspective view of a photographic camera, showing my new design.

Fig. 2 is a rear perspective view of the same.

I claim:

The ornamental design for a photographic camera, as shown.

LUCIEN ANTOINE REGIS BOUCHETAL.
